(57) **CLAIM**

The ornamental design for an operator cabin of power shovel, as shown and described.

DESCRIPTION

FIG. 1 is a perspective view of an operator cabin of power shovel showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a cross sectional view taken along line 8—8 in FIG. 6.

The broken line showing is for illustrative purposes only and forms no part of the claimed design.
